United States Patent Office

Des. 198,453
Patented June 16, 1964

198,453

BEAKER OR THE LIKE

Edwin G. Weichselbaum, Normandy, Mo., assignor to Brunswick Corporation, a corporation of Delaware

Filed Nov. 14, 1963, Ser. No. 77,430

Term of patent 7 years

(Cl. D16—1)

FIG. 1 is an elevational view of a beaker embodying my novel design;

FIG. 2 is a top plan view of the beaker of FIG. 1;

FIG. 3 is a sectional view taken along the line 3—3 of FIG. 1; and

FIG. 4 is a bottom plan view of the beaker of FIG. 1.

I claim:

The ornamental design for a beaker or the like, as shown.
